UNITED STATES PATENT OFFICE.

EDWARD H. JOHNSON, OF NEW YORK, N. Y., ASSIGNOR TO BERGMANN & COMPANY, OF SAME PLACE.

SWITCH.

SPECIFICATION forming part of Letters Patent No. 443,606, dated December 30, 1890.

Application filed January 21, 1885. Serial No. 153,487. (No model.)

To all whom it may concern:

Be it known that I, EDWARD H. JOHNSON, of New York, in the county and State of New York, have invented a certain new and useful Improvement in Switches for Electric Circuits, of which the following is a specification.

The object of this invention is to control the separate circuits of several—two or more—electric lamps or groups of electric lamps by a single switch, so that the movement of such switch will throw such lamps or groups of lamps successively into circuit or successively out of circuit, whereby one or all or any intermediate number of such lamps or groups of lamps may be placed in circuit, and thus lighted, or cut out of circuit and thereby extinguished.

In carrying my invention into effect I employ a moving body provided with a contact permanently in connection with a conductor of the main or supplying circuit and with two or more other contacts adapted to be brought by the movement of said body successively into connection with terminals of the two or more branch circuits with which the two or more lamps or groups of lamps which it is desired to effect by the movements of the switch are connected. The other terminal of each of said branch circuits is permanently connected with the other conductor of the main or supplying circuit. The moving body is preferably a revolving cylinder of insulating material having upon its surface a continuous metal ring, on which bears a spring, which is a terminal of a conductor of the main or supplying circuit, and having also two or more non-continuous metal contacts or portions of rings, upon the plane of each of which bears a spring which forms a terminal of a branch circuit. All said non-continuous rings are connected permanently with the main continuous ring. Said non-continuous rings are so arranged relatively to each other or one another that their ends or the points at which the springs leave them are in different vertical planes while the springs are in the same vertical planes, so that the circuits are closed successively or broken successively. I may employ upon the same cylinder two or more sets of branch terminals,

whereby during a single revolution of the cylinder the circuits are closed and broken two or more times, and thus the whole operation of the switch is performed by only a part of the revolution of the cylinder.

55

My invention is illustrated in the accompanying drawings, in which—

Figure 1 is a view in elevation of a switch embodying my invention having two sets of branch-circuit terminals; Fig. 2, a similar view of the switch with only one set of branch-circuit terminals. Fig. 3 is a view of the cylinder of Fig. 1 developed into a flat surface and a diagram of the circuits, and Fig. 4 is a similar view of the switch of Fig. 2.

65

A is a cylinder of suitable insulating material, having a central spindle a, which turns in bearings in a supporting-frame B, and is provided with a wheel C or any other suitable key or handle for turning it.

70

I will first describe the simple switch shown in Figs. 2 and 4.

Upon the surface of the cylinder A is a continuous metal ring or band E.

F, F', and F² are metal contact-bands, each of which extends about half-way around the cylinder, and G, G', and G² are corresponding "dead-plates" not connected with the circuits, whose object is to provide substantially continuous surfaces in the paths of the contact-springs.

Secured in any suitable manner to the frame B is a spring H, which bears constantly on the continuous band or ring E, and springs I, I', and I², which bear upon the contacts F, F', F² or the dead-plates G, G', G² as the cylinder is revolved.

1 2 are main conductors or terminals of the source of electricity. Main conductor 1 is connected by wire 3 with spring H, and main conductor 2 is connected by wires 4, 5, and 6, through lamps x x' x², with the contact-springs I, I', I².

By means of wires c, c', and c² the continuous ring E is connected with all the non-continuous contacts F, F', and F². These wires are preferably soldered or otherwise secured to the under sides of the contacts. The metal rings and connecting-wires upon the cylinder thus form a moving conducting-body perma-

100

nently in connection with the main conductor-terminal and adapted to be brought into connection with one or all or any intermediate number of the branch conductor-terminals.

- 5 The operation of the switch is as follows: When the switch-contacts are as shown in the figures, all the lamps are in circuit; but on turning the switch in the direction indicated by the arrow the spring I first leaves 10 the contact F and passes upon the dead-plate G, breaking the circuit of lamp x. Next the spring I' leaves contact F' and breaks the circuit of x', and finally spring I² leaves F² and extinguishes lamp x². A continuation 15 of the revolution brings I upon F, then I' upon F', and then I² upon F², the lamps being thus brought successively into circuit again. It is evident that each contact of the switch may control instead of a single lamp a group 20 of lamps, as shown in Fig. 3.
- In the switch shown in Figs. 1 and 3 there are two contacts f f' f' f' or f² f² and two dead-plates g g' g' g' or g² g² in the path of each branch-circuit spring. The contacts for 25 each spring are connected together by a wire d. When a spring is on either of the contact-plates in its path, circuit is closed to the group of lamps x controlled by that spring, and when it is on either of the dead-plates the circuit 30 of such lamps is broken. Thus a half-revolution of the switch successively lights all the lamps and then successively extinguishes them, after which a continuation of the movement in the same direction performs the same 35 operations again. It is evident that the springs may be made to revolve upon the cylinder, instead of the cylinder under the springs, and also that the ends of the springs may be arranged in different vertical planes instead 40 of the ends of the ring-contacts.

Either of the above-described forms of switches may be employed in any situation and for any purpose where it is desired to control a number of circuits and to close and 45 break said circuits successively.

The switch may be used to control the separate lights of an electrolier, and for this purpose may be placed upon the fixture or in any convenient place to which the lamp-circuits 50 may be brought, or it may be employed to control groups of lights, as the lights of dif-

ferent rooms or lights in different parts of a room or building.

What I claim is--

1. The combination, with a movable body 55 of insulating material, of a contact-piece carried thereby permanently in connection with the conductor of the main circuit, and two or more overlapping contact-pieces carried by and terminating at different points on the surface of the movable body, and consisting of non-continuous strips extending around the movable body, the breaks in the strips being arranged diagonally on the surface, and co-operating contacts for said overlapping contact-pieces connected with the other conductor of the main circuit, whereby one or more of the overlapping pieces may be connected with the continuous contact, substantially as forth.

2. In an electrical switch, the combination of a spring from which a main-circuit wire extends, a conducting-body with which the spring is continuously in contact, a series of springs from which wires of branch circuits extend, 75 and a moving conducting-body consisting of connected non-continuous strips on which said springs bear, said moving conducting-body passing under all the branch-circuit springs for a portion of its length, the end terminating in a line diagonal to the end of the contact-springs, whereby one or more of the branches may be switched into circuit, substantially as described.

3. In an electrical switch, the combination 85 of a revolving cylinder, a continuous ring, and two or more non-continuous rings on said cylinder, the conducting-sections of said rings overlapping for a part of their length, a spring forming a main-circuit terminal bearing on said continuous ring, and springs forming branch-circuit terminals bearing on said non-continuous rings, said continuous rings and said non-continuous rings being connected together, substantially as set forth.

This specification signed and witnessed this 14th day of January, 1885.

EDWARD H. JOHNSON.
